IMPROVEMENT IN FENCE.

SIMEON P. TUTTLE, OF DECATUR, MICHIGAN.

Letters Patent No. 60,286, dated December 4, 1866.

SPECIFICATION.

TO ALL WHOM IT MAY CONCERN:

Be it known that I, S. P. TUTTLE, of Decatur in the county of Van Buren, and State of Michigan, have invented certain new and useful improvements in Fences; and I do hereby declare that the following is a full, clear, and exact description of the same, reference being had to the accompanying drawings and to the letters of reference marked thereon.

In the annexed drawing, making part of this specification, A and B represent two sections or pannels of a portable fence. The boards of which these pannels are formed project about six inches at each end beyond the battens E E, which bind them together. C represents the fence post. This post has two or more staples driven into it, as seen at D D. The two pannels are placed against the posts, with the projecting ends of the boards of which they are formed lying against each other, and are held to the post by means of the staples D D, the ends of the pannels resting on said staples. F represents a cap, which is pivoted to the top of the post C, as seen at X. By turning this cap, as shown in the figure, the pannels are prevented from being raised out of the staples, and can only be drawn out endwise. The fence pannels could be held together by the staples alone, so long as they were not raised up; but by the use of the cap they are held more securely in position, and cannot be raised without removing said cap. With this arrangement it will readily be seen that by simply turning the cap any pannel can be removed for the purpose of making a gate. The L-shaped staples or screws D D can be turned one-quarter around for the extraction of a single rail and insertion of one instead, should it become necessary, without taking off the entire pannel. It will be observed that each of the pannels, A or B, of themselves, form a portable gate.

Having thus fully described my invention, what I claim as new, and desire to secure by Letters Patent, is—

The post C, provided with the L-shaped screws or staples D D and cap F, when used in combination with the fence sections A or B, constructed as described, to form a portable fence, when arranged and used as and for the purposes set forth.

As evidence that I claim the foregoing, I have hereunto set my hand in the presence of two witnesses.

SIMEON P. TUTTLE.
